James G. Norton

UNITED STATES PATENT OFFICE.

JAMES G. NORTON, OF LEONIA, NEW JERSEY.

PROCESS AND APPARATUS FOR MAKING CUPS.

Application filed April 11, 1922, Serial No. 551,709. Renewed September 17, 1926.

This invention relates to a process and apparatus for making cups and particularly cups formed to provide a frusto-conical body portion for containing a substance to be eaten and a substantially cylindrical handle portion depending from the body portion.

In accordance with the process of this invention, the cup is formed from a blank of generally circular form in two steps, the first step consisting in shaping the blank generally in the form of a cup corresponding in diameter to the diameter of the handle portion of the completed cup and the second in spreading out the upper, open end of the blank into the form of the frustum of a cone. In order to facilitate the shaping of the blank into cup-like form and the subsequent spreading out of its upper end into conical form, the blank is preferably pleated or crimped.

An important feature of the improved apparatus resides in the provision of means for automatically shaping the blank into the form of a cup corresponding in diameter to the handle portion of the finished cup and means for automatically spreading out the upper end of the blank into the general form of a cone to complete the cup.

A still further feature of the improved apparatus contemplates the provision of a die member having means co-acting therewith for inserting a blank into it and imparting to the blank at one of its portions a shape like that of the handle portion of a completed cup and other means for imparting to the other portion of the blank a frusto-conical form to constitute the body portion of the cup.

Still other objects and features of the invention will appear as the description proceeds and will be pointed out in the appended claims.

In the drawings in which like reference numerals designate like parts in the various views;

Fig. 1 is a sectional view in elevation showing the means for inserting a blank into the main die member and imparting the initial shape to the blank;

Fig. 2 is a plan view taken substantially along the line 2-2 in Fig. 1;

Fig. 3 is a view in plan of the main die member;

Fig. 4 is a view in sectional elevation

taken substantially along the line 4-4 of Fig. 3 and showing the auxiliary die member for shaping the body portion of the cup;

Fig. 5 is a view in elevation taken substantially along the line 5-5 of Fig. 4;

Fig. 6 is a detail view of one of the devices mounted on the main die member for engaging the upper end of the blank during the uni-directional laying of the pleats; and

Fig. 7 shows the completed cup.

The illustrated apparatus is illustrative of one means by which the process of this invention may be carried out and will be hereinafter described for the sake of convenience in connection with the machine shown in United States Letters Patent to Claussen et al., No. 1,047,173, granted Dec. 17, 1912. It will be understood, however, that the present embodiment of the invention is merely by way of example and that the apparatus of the invention may be incorporated in machines of various structures and designs without departing from the principles of the invention.

The illustrated apparatus includes a rotary carrier 12 provided in its outer portions with circular openings 13. The annular border of each of the circular openings 13 carries a ring 14. Each of the rings 14 in turn carries a number of radially arranged plaiting levers 15, all of which turn upon annularly arranged fulcrums 16 respectively and are all carried and held in their horizontal positions by an annular wire 17 which occupies the slot 18 in the outer end of each lever and is normally yieldingly held downward by a series of springs 19 arranged around it at intervals. Each of the levers 15 has its inner end laterally extended and rounded as indicated at 20, Fig. 1. The parts above described may be and as shown are substantially as shown in the above-mentioned patent.

Carried on the machine frame for rotation with the carrier 12 is a vertical sleeve 21 within which is a vertical rod 22. The sleeve 21 and rod 22 are reciprocated vertically by suitable means (not shown), but which may be substantially as shown in said Letters Patent.

Each of the sleeves 21 has its lower end encircled by a ring 37 which is fixed to the sleeve, and the ring 37 is in turn encircled by the upper border of the cup-shaped mandrel 38. The wall of the mandrel 38 is pro-

vided with uniformly spaced longitudinal slots 39 equal in number to the plaiting levers 15 and through which a link 40 extends from its connection with the rod 22. The 5 lower ends of the links 40 are respectively pivoted to an equal number of followers 41, the inner ends of which are pivoted in the lower ends of the slots 39 respectively and the bodies of which alternately retreat into 10 the slots 39 and advance out of them.

Mounted to rotate on the machine frame at a level below that of the carrier 12 is a table 51 provided with radial slots 52 in which the main die members 53 are slidably 15 and rotatably received. The radial slots 52 are arranged around the border of the table 51, and the die members 53 are normally pressed outwardly to the outer ends of the slots by springs 54 interposed between 20 ears 55 extending upwardly from the table 51 and a foot 56 engaging an annular groove 57 in the die 53 and connected to the end of a rod 58 slidably mounted in the ear 55.

The die members 53 are generally circular 25 in contour and each of said members is provided on its upper surface with guideways 60 disposed at diametrically opposite sides of the center of the die. Mounted in the guideways 60 for radial sliding movement 30 relatively to the die 53 are bars 61 each of which is formed in its inner edge with a semi-circular recess 62, so arranged that when the bars 61 are in their innermost positions in which their ends engage each other 35 at opposite sides of the recesses, the recesses define a circular opening. The bars 61, as shown in Fig. 4, extend outwardly over projections 63 extending peripherally from the upper portion of the die 53 and are normally 40 held inwardly in engagement with each other by springs 64 secured at their inner and outer ends to posts 65 on the guide ways 60 and posts 66 upstanding from the bars.

Each of the die members 53 is formed in 45 its lower portion with a bore 67 corresponding in size and shape with the handle portion 68 of the cup, and in its upper portion with a frusto-conical die face 69 consonant in size and shape with the body portion 69' 50 of the cup. The bore 67 is preferably substantially cylindrical but is tapered downwardly to a sufficient degree to enable the the finished cups to be nested, and the recesses 62 of the bars 61 in the innermost 55 positions of the bars are arranged substantially in alignment with the bore 67.

The table 51 (Figs. 1 and 4) is provided centrally below the radial slots 52 with slots 70 which receive bosses 71 depending centrally from the die members 53, and mounted 60 for rotation with the carrier 12 as shown in the above-mentioned Letters Patent is a circular disk 11 arranged for engagement with the peripheries of the dies 53 as seen 65 in Fig. 1. As the disk 11 and table 51 are

rotated in opposite directions or, in other words, so that the adjacent portions of their peripheries move in the same direction, the disk 11 successively engages the dies 53 and moves them inwardly on the table 51 from 70 their normal positions in which their bosses 71 abut against the outer ends of the slots 70, as shown in broken lines in Fig. 3, to the position shown in Fig. 1. While the dies 53 are being thus moved inwardly in the 75 slots 52, they are rotated in a clock-wise direction, as seen in Fig. 2, by means of rack teeth 72 on the dies meshing with correspondingly formed teeth on a rack 73 secured to the table 51 at one side of the 80 slot 52.

The manner of operation of my improved apparatus, as thus far described, is as follows: A circular disk of paper or other suitable material is placed on the plaiting levers 85 15. Then the upper plaiting mechanism, including the followers 41 which are then, together with the mandrel 38 located above the levers 15, descends toward and into the lower plaiting mechanism. At the beginning 90 of the joint operation of such mechanisms, the paper disk is bent into a shallow, saucer-like form, and as the operation proceeds the saucer-like form is gradually changed into a pleated cup-shaped form. 95 During the downward movement of the mandrel 38, which is of a size and shape corresponding with that of the bore 67 of the die 53, the followers 41 hold the rising and 100 inwardly moving sides of the paper blank 105 against the ends of the levers 15, while gradually retreating toward the mandrel 38. The result of the action of the plaiting mechanisms is to cause the blank at its sides to be plaited or collapsed into uniform narrow plaits and to be inserted into the die 53, as seen in Fig. 1, through the opening 110 formed by the semi-circular recesses 62 of the bars 61. By reference to Fig. 1, it will be seen that the mandrel 38 has been depressed to an extent such that the ends 20 of the levers 15 have been left above the upper edge of the plaited cup-shaped blank, the blank at this stage of the operation of the machine being slender and elongated so 115 as to resemble somewhat a human finger.

The sleeve 21 and rod 22, connected respectively to the mandrel 38 and links 40 may be operated by suitable cam means such as is shown in said Letters Patent, the arrangement of the cams being such as to cause the followers 41 to assume an inclination corresponding to the taper of the bore 67 of the die 53 and to properly enter the opening in the bars 61.

The inward radial motion of each of the dies 53 is accompanied by a rotary motion about its center in the direction indicated by the arrow in Fig. 2, produced by the teeth 72 on the dies meshing with those of the 130

rack 73. The function of this rotary motion is to lay all of the folds or pleats of the blank in the same direction, it being understood that the mandrel 38 and the followers 41 do not turn with the die 53 but are relatively stationary, and that the turning of the die carries the outer bends of the blank positively in the same direction by reason of friction between the bends of the blank and the surfaces of the bore 67 and the opening formed by the recesses 62 of the bars 61. It will also be understood that the bars 61 partake of the turning movements of the dies 53, and are thus caused to support the blank at its upper end and to co-operate with the lower portion of the die 53 in laying the folds of the blank in a common direction. After each mandrel 38 has thus completed the preliminary shaping of a blank in one of the dies 53, it is withdrawn from the die by operation of the sleeve 21 and rod 22. The sleeve 21 and rod 22 are so operated as to cause the mandrel 38 to be raised above the plaiting levers 15 which are then swung by the springs 19 into a position in which their upper edges are horizontal. The followers 41 are swung outwardly from their upper ends as the mandrel 38 rises from the die 53, assuming a position parallel to and spaced above the upper edges of the levers 15, and the carrier 12 in its rotation moves each of the mandrels 38 and the plaiting levers 15 associated with them away from the table 51 to a position to receive another blank. Since the blank is depressed by the mandrel 38 so as to carry its upper edge below the levers 15, the rounded inner ends of the levers positively prevent the blank from rising with the mandrel 38 and insure that the blank will be retained in the die 53 in proper position for the performance of a subsequent operation upon it.

After the blank has thus been formed into a slender, finger-like shape, as seen most clearly in Fig. 4, it is carried by rotation of the table 51 and while still contained in the die 53 away from the carrier 12. When the die 53 has been moved clear of the carrier 12, a male die 74 is lowered into it. One of the male dies 74 is associated with each of the dies 53, and the male dies may be operated as described in the above-mentioned Letters Patent. The die 74 comprises a lower, downwardly tapered, generally cylindrical portion 75 adapted to fit within the bore 67 of the die 53 and a frusto-conical portion 76 at its upper end shaped to fit within the upper face 69 of the die 53. As shown, the die 74 is mounted between bifurcations 77 of its operating arm 77', and its upper portion 76 terminates in an annular flange or rib 78.

Mounted for movement with the die 74 are laterally extending arms 79, and depend-

ing from the outer ends of the arms 79 are cam bars 80 arranged for engagement in longitudinal slots 81 in the bars 61 upon depression of the die 74 into the die 53. When the bars 61 are in their innermost positions (Fig. 4), the slots 81 extend somewhat beyond the outer ends of the guideways 60 and the projections 63 on the die 53 in position to receive the relatively slender tips 82 of the cam bars 80. The outer ends of the slots 81 may be rounded, as indicated at 83 (Fig. 4), or, if desired, the bars 61 may be provided with suitable anti-friction rollers located adjacent to the outer ends of the slots 81 for engagement with the cam surfaces 84 of the bars 80. The bars 61 are normally held inwardly by springs 64 connected at their inner and outer ends to posts 65 and 66 on the guideways 60 and bars 61 respectively as heretofore stated.

The last-described parts are so arranged that as the die 74 is lowered within the die 53, the cam bars 80 retract the bars 61 against the resistance of the springs 64 in advance of the movement of the die 74, so as to prevent the blank from being gripped between the die 74 and the bars. As appears clearly from Fig. 4 also, the inner ends of the guideways 60 are spaced outwardly from the upper edge of the face 69 of the die 74, and the bars 61 are arranged to be withdrawn outwardly from the upper edge of the face 69, to an extent such as to allow the flange 78 at the upper end of the die 74 to be lowered into engagement with the top of the die 53. Other means for retracting the bars 61 out of the way of the die 74 in its downward movement will suggest themselves to a mechanic skilled in the art and may be employed without departing from the principles of the invention.

In the operation of the die 74, the pleated upper end of the blank is gradually opened out by the upper portion 76 of the die into a frusto-conical form, and the die 74 may be pressed firmly into the die 53 to set the folds or pleats of the cup into a permanent condition. The means for pressing the die 74 into the die 53 and for causing the folds of the cup to be permanently set may be substantially as shown in the above-mentioned Letters Patent.

The arms 77' on the table 51 having the bifurcations 77 and carrying the dies 74 are preferably arranged substantially radially of the table 51 and the arms 79 carrying the cam bars 80 are arranged substantially at right angles to the die carrying arms. It will further be understood that the dies 74 co-act with the dies 53 only when the last-named dies are free of the disk 11 and are hence maintained in the outer ends of the slots 52 by the springs 54. Consequently, it will be apparent that the bars 61 on the dies 53 normally and at the time of their

engagement with the cam bars 80 extend in a generally tangential direction with respect to the table 51.

The bosses 71 of the dies 53 are provided with headed pins or plungers 85 which are moved upwardly simultaneously with the elevation of the dies 74 from the dies 53 to detach the completed cups from the inner surfaces of the dies 53 and to cause them to move upwardly with the dies 74. This upward movement of the plungers 85 may be effected by a stationary cam 86 shown diagrammatically in Fig. 4.

Housed in the die 74 is a second pin 87 having an eye 88 at its upper end which receives one end of a finger 89 fulcrumed in the arm 77' at 90 and normally held upwardly by a spring 91. After a male die 74 has been elevated from a die 53 carrying a completed cup with it, a roller 92 on the finger 89 engages a relatively fixed part (not shown) as the table 51 continues to rotate and causes the pin 87 to be depressed below the lower end of the die 74 thus detaching the cup from the die 74 and delivering it from the machine.

From the foregoing it will be understood that the process of this invention consists in one of its aspects in forming a cup having a frusto-conical body portion and a more nearly cylindrical handle portion by first shaping a blank into the form of the completed cup and then settling the blank into a permanent condition. In a more particular aspect, the invention also contemplates the shaping of a blank by pleating into a finger-like shape corresponding with the diameter of the handle portion and then opening out the end of the blank into the form of a frustum of a cone.

I believe that I am the first to form a cup having a frusto-conical body portion and a more nearly cylindrical handle portion from a single blank, and I desire to obtain broad patent protection on a process for making such a cup involving the pleating of the blank.

The bars 61 may, if desired, be enlarged vertically adjacent to the recesses 62 to provide an increased area for engagement with the blank, and the upper edges of the recesses 62 may be beveled outwardly or rounded to facilitate the entrance of the blank into the opening constituted by the recesses.

Having fully described the invention, what is claimed is:

1. The process of making a cup which consists in shaping a blank into a substantially frusto-conical body portion and a more nearly cylindrical handle portion and then setting the blank in permanent condition.

2. The process of making a cup which consists in shaping a blank by pleating or crimping into a substantially frusto-conical

portion and a more nearly cylindrical handle portion and then setting the blank in permanent condition.

3. The process of making a cup which consists in shaping a blank by pleating into a substantially frusto-conical portion and a nearly cylindrical handle portion, laying the folds of the blank in one direction, and then setting the blank in permanent condition.

4. The process of making a cup having a substantially frusto-conical body portion and a more nearly cylindrical handle portion which consists in shaping a blank into a finger-like shape corresponding in diameter at its lower end with the handle portion of the cup and then spreading out the open end of the cup into a frusto-conical form.

5. The process of making a cup having a substantially frusto-conical body portion and a substantially cylindrical handle portion which consists in shaping a substantially circular blank by pleating into a finger-like form corresponding in diameter at its smaller end with the handle portion of the cup and then spreading out the open end of the cup into a frusto-conical form.

6. In an apparatus of the class described, means for supporting a blank and means for shaping the blank into the form of a cup having a frusto-conical body portion and a more nearly cylindrical handle portion and for setting the cup in permanent condition.

7. In an apparatus of the class described, a die member having a frusto-conical face and a more nearly cylindrical bore and means co-acting with said die to form a cup having a body portion shaped in accordance with said face and a handle portion shaped in accordance with said bore.

8. In an apparatus of the class described, a die member having a frusto-conical face and a more nearly cylindrical bore, means for inserting a blank into said die and forming the blank into a finger-like shape corresponding in diameter at one of its ends with said bore, and means for spreading out the open end of the blank against said frusto-conical face.

9. In an apparatus of the class described, a die member having a frusto-conical face and a more nearly cylindrical bore, members mounted on the die member above the bore and formed to present an opening substantially in alignment with the bore means for pleating a blank and inserting it into said opening and said bore to shape the blank into a finger-like form, a male die comprising portions constructed to fit within the bore of said first-mentioned die member and against said face, and means for moving said second-mentioned members out of the way of the male die upon depression of the male die into said die member.

10. An apparatus according to claim 8 in which the die member and the members

mounted upon it are turned to lay the fold of the blank in a common direction.

11. An apparatus according to claim 6 comprising means for detaching a completed cup from the die member and delivering it from the machine.

12. In an apparatus of the class described, means for forming a blank into a finger-like form and means for spreading out the open 10 end of the blank into the form of the frustum of a cone.

13. In an apparatus of the class described, a die member formed with a bore to receive a blank, blank engaging members arranged 15 on the entrance side of the bore, and means for moving said members away from the entrance to the bore.

14. In an apparatus of the class described, a die member formed with a bore to receive

a blank, means for supporting the sides of 20 a blank during its insertion into the bore, and means for moving said supporting means toward and from said bore.

15. In an apparatus of the class described, a die member formed with a bore to receive 25 a blank, a second die movable into and out of the bore, means for guiding a blank during its insertion into the bore, and means for moving said guiding means out of the path of movement of said second die. 30

16. In an apparatus of the class described, a die member formed with a bore to receive a blank and means on said member for guiding a blank during its insertion into said bore. 35

In testimony whereof I affix my signature.

JAMES G. NORTON.
